OIL-WELL APPARATUS

Application filed November 28, 1928. Serial No. 322,456.

The object of our invention is to provide a simple apparatus by the use of which oil may be automatically raised from a well without disturbing the sand at the bottom 5 of the well. The invention provides means whereby fluid pressure, such as compressed air, may be admitted through the tubing to an oil-collecting chamber and act upon the oil in said chamber to force the same 10 through the well casing to the mouth of the well. The invention also provides means at the surface whereby the flow of the oil will automatically operate to control the admission of the pressure fluid to the tubing and 15 thereby regulate the drawing of the oil from the well. An apparatus embodying the invention is illustrated in the accompanying drawings and will be hereinafter fully described, the novel features being 20 particularly defined in the appended claims.

In the drawings:

Figure 1 is an elevation of the operating parts of the mechanism, the well casing being shown in section; 25 Fig. 2 is an enlarged vertical section of the oil-collecting chamber; Fig. 3 is an enlarged detail section of a check valve which may be inserted in the tubing if desired; 30 Fig. 4 is an enlarged sectional elevation of the flow-controlling apparatus which is provided at the ground surface, and Fig. 5 is a view, partly in horizontal section and partly in plan, of a portion of the apparatus shown in Fig. 4.

In the drawings, the reference numeral 1 indicates the well casing which may be of the usual or any approved form and extends to the bottom of the well in the usual manner. Supported concentrically within the casing is the tubing 2 which at its lower end is formed integral with or permanently united with an enlarged portion 3 constituting an oil-collecting chamber, these parts 45 being preferably united by welding or swaging so that the joint will be leak-proof, and interposed between the enlargement or oil-collecting chamber 3 and the casing 1 is a packing 4 which may be of any known or 50 approved form, this packing serving to pro-

vide a leak-proof seal between the oil-collecting chamber and the casing whereby oil admitted to the casing above the packing will be prevented from flowing back into the well. In the bottom of the chamber 3 is 55 a check valve 5 which opens upwardly and admits oil from the well into the chamber, and mounted within this chamber at one side of the same is an outlet tube 6 which opens through the side of the chamber above 60 the packer 4, as shown at 7. In the lower end of the outlet tube 6 is a check valve 8 which opens upwardly.

At the mouth of the well, there is provided a head or cap 9 of any approved form 65 and extending through this cap to enter the upper end of the tubing 2 and connected with the tubing by an air-tight joint is a fluid pressure pipe 10 which is connected at its upper end through a T-coupling 11 with 70 an inlet pipe 12 and an exhaust pipe 13. The inlet pipe 12 is connected with an air compressor or blower of any approved form and which has been omitted from the drawings as, in itself, it forms no part of the 75 present invention while the exhaust pipe 13 may be led to any desired point and opens into the atmosphere. Fitted to the inlet pipe and the exhaust pipe are casings 14 each of which houses a check valve 15 80 whereby the flow through the pipes is controlled and these check valves are carried by links or stems 16 rising through the casings 14 and pivoted at their upper ends to a lever 17 which is fulcrumed midway its ends 85 upon a post 18 provided at any convenient point, as upon the T-coupling 11. The check valves 15 work alternately and in opposition so that, when the flow through the inlet pipe is opened, the flow through the exhaust pipe will be cut off and, consequently, the fluid under pressure will be caused to flow down through the pipe 10 and the tubing 2 to enter the oil-collecting chamber 3. When the position of the check valves is reversed so that the exhaust pipe 90 is opened, the inlet will be cut off and the pressure fluid will then rise through the tubing and the pipe 10 to escape through 95 100 the pipe 12.

the exhaust pipe, oil being then admitted to the oil-collecting chamber.

Extending laterally from the head or cap 9 is an oil outlet pipe 19 which enters a 5 governor tank 20 at the bottom of the same, and this oil outlet pipe is equipped adjacent the governor tank with a check valve 21 of any approved design which will permit the oil to flow into the tank but will close when 10 the oil tends to flow from the tank. Within the governor tank 20 is a loose central rod 22 having abutments 23 thereon near its upper and lower ends, as shown clearly in Fig. 4, and slidably mounted on and guided 15 by said rod is a float 24. A rocking arm or lever 25 is pivotally mounted upon the side of the tank and extends through the same and has its inner end connected with the rod 22 whereby it forms a support for said 20 rod while the outer end of the lever is pivotally connected with a rocking arm or lever 26 which is in the form of a bail, shown most clearly in Fig. 5, having its inner arms pivoted upon the pipe 10 at the opposite 25 sides thereof and having said arms brought together outwardly from the pipe and fixed to a cross bar 27. At the opposite side of the pipe 10, a similar lever or rocking arm 28 is provided, the inner ends of this rock- 30 ing arm 28 being pivoted upon the pipe on the same pivots as the arm or lever 26 and the outer end of the arm 28 being secured to a cross bar 29 corresponding to the cross bar 27. A connecting rod 30 is pivoted to 35 the cross bar 29 and rises therefrom to the lever 17 to which its upper end is pivoted, as clearly shown in Figs. 1 and 4. Secured upon the pipe 10 at points above and below the pivots 31 which support the arms 26 and 40 28 is a guiding frame 32 which projects laterally to opposite sides of the pipe and comprises mating parallel bars or straps between which the outer end portions of the respective arms 26 and 28 play, as shown in 45 Fig. 5. The outer portions of these guide frames are constructed with arcuate slots 33 having the pivot 31 as their centers, and stop pins 34, carried by the arms 26 and 28, play in the respective slots. Secured to and 50 extending between the corresponding ends of the cross bars 27 and 29 are contractile springs 35 which tend constantly to draw the said cross bars and the ends of the arms 26, 28 toward each other, as will be under- 55 stood.

Leading from the governor tank 20 at the bottom thereof is a pipe 36 which extends to a storage tank, and the governor tank and the parts cooperating therewith are prefer- 60 ably elevated with respect to the storage tank so that the oil may flow through the delivery pipe 36 by gravity. Interposed in the delivery pipe 36 adjacent the governor tank 20 is a siphon tube 37 which rises to 65 the height to which the oil is intended to

rise in the tank and in the outlet side of the siphon is a cut-off valve 38 of any approved form and in the delivery pipe between the members of the siphon is a similar cut-off valve 39 whereby the flow of the oil may be regulated and the system drained if repairs or cleaning should be necessary. 70

If the oil should be heavy so that it does not rise readily to the mouth of the well, check valves, such as shown in Fig. 3, may be provided at such intervals in the length of the tubing 2 as may be desirable. These check valves each comprises a nipple 40 threaded through the side of the tubing collar or the upper end of the oil chamber and having its bore somewhat enlarged at its outer end, as shown at 41. A ball valve 42 is mounted in the enlarged bore 41 and is normally held to the seat provided by the end of the enlarged bore under the influence of a spring 43 disposed between the ball and a stop 44 provided near the outer end of the bore, as clearly shown in Fig. 3. 75 80 85

It is thought the operation of the apparatus will be readily understood from the foregoing description, taken in connection with the accompanying drawings. The capacity of the governor tank 20 and the oil-collecting chamber 3 should be the same or approximately the same so that, in the 90 operation of the mechanism, when the governor tank is discharging the oil-collecting chamber will be filling and the oil-collecting chamber will be filled at or about the instant that the governor tank becomes 95 empty. Assuming that there is no pressure in the pipe 10 and the tubing, oil will rise past the check valve 5 and fill the collecting chamber 3, the float 24 at this time being at the bottom of the governor tank and resting on the lower abutment 23. The oil entering the oil-collecting chamber 3 will, of course, pass into the oil discharge tube 6 and rise in said tube to the same level that it reaches in the chamber 3. If the check 100 valves 15 be shifted so that the exhaust pipe will be closed and the inlet pipe opened, fluid pressure will flow down through the pipe 10 and the tubing 2 and act upon the surface of the oil in the chamber 3 to force 105 the oil out through the pipe 6 into the space between the casing and the tubing, and back flow of the oil in the casing will be prevented by the packing 4 and by the seating of the check valve 8, it being under- 110 115 120

stood that the check valve 5 will also be closed under the influence of the pressure exerted by the pressure fluid. When all of the oil collected in the chamber 3 has been forced into the casing, the exhaust pipe 13 125 is opened and the in-flow of pressure fluid cut off so that oil will be again admitted to the collecting chamber 3, and this process is continued until eventually the oil reaches the mouth of the well and flows from the 130

casing through the pipe 19 into the governor tank 20. The pressure fluid is then permitted to flow without further attention on the part of the operator and the oil entering the governor tank will pass under the float 24 and cause the same to rise in the tank. Eventually, the float will impinge against the upper abutment 23 and lift the rod 22, thereby rocking the lever 25 so that the lever or rocking arm 26 will be drawn downwardly to the position shown in Fig. 4. As the arm 26 passes the dead center, so that the angle formed by said arm and the arm 28 is less than one hundred and eighty degrees, the springs 35 will contract so that the arm 28 will be drawn downwardly with a snapping action and the valves 15 will be reversed, the further inflow of pressure fluid being cut off and the exhaust pipe opened so that the pressure may escape. The oil in the governor tank will now flow therefrom through the delivery pipe 36, the flow being controlled by the cut-off valve 38 and induced by the siphonic action. The float will, of course, descend with the level of the oil in the governor tank and the pressure of the outflowing oil will close the check valve 21 so that further flow of oil into the governor tank will be prevented. While the oil is discharging from the governor tank, additional oil will be flowing into the collecting chamber inasmuch as the pressure is cut off therefrom. When the float 24 comes into contact with the lower abutment 23, the rod 22 will be drawn downward and the levers 25, 26 and 28 will be reversed so that the escape of pressure fluid will be cut off and inflow of the same again established to act upon the oil in the collecting chamber and raise the same to the surface. It will thus be seen that we have provided a very simple direct acting mechanism whereby the flow of oil will be automatically controlled and the oil raised to the surface and stored with minimum effort and cost. The pressure fluid does not flow past the oil-collecting chamber and, consequently, does not reach the sand at the bottom of the well so that the sand is permitted to settle and separate from the oil which will be clean as it enters the collecting chamber. Should the oil be very heavy and its outflow from the collecting chamber at a less rate than the inflow of the pressure fluid, pressure will be built up in the tubing 2 and will eventually overcome the pressure exerted on the ball valve 42 by the oil and the spring 43 so that the valve will be opened and some pressure fluid permitted to escape past the same to mingle with the oil in the casing above the packer 4 and thereby aerate and lighten the oil so that it will more readily flow to the surface.

Having thus described the invention, we claim:

1. Oil well apparatus comprising an oil-collecting chamber, a fluid pressure conduit leading into the top of said chamber, a governor tank, means for conveying oil from said collecting chamber into the governor tank, an inlet pipe leading into the fluid pressure conduit, an exhaust pipe leading from said conduit, said inlet and outlet pipes having a common connection with the conduit, reversely acting valves in said inlet pipe and in said exhaust pipe respectively controlling the flow through the same and the conduit, a single lever fulcrumed between its ends and connected at its ends with the respective valves, and cooperating rocking arms having a common pivot, retractile springs connecting the outer ends of said arms, a connection between one of said arms and the lever, and means connected to the other of said arms and controlled by the outflow of oil for rocking the arms. 70 75 80 85

2. Oil well apparatus comprising an oil-collecting chamber, means for supplying fluid under pressure to said chamber to discharge oil therefrom, a governor tank, means for conveying the oil from the oil-collecting chamber into said tank, oppositely acting valves controlling the inflow and outflow of the pressure fluid, cooperating rocking arms having a common pivot, retractile springs connecting the outer ends of said arms, a connection between one of said arms and the valves, a float within the governor tank, a lever connected with the opposite one of said rocking arms and operated by said float, and means for limiting the movement of the rocking arms. 90 95 100 105

In testimony whereof we affix our signatures.
